THORWALD H. HANSEN

UNITED STATES PATENT OFFICE

2,349,961

APPARATUS FOR CASTING CONCRETE
AROUND PILES

Thorwald H. Hansen, Avenel, N. J.

Application May 21, 1942, Serial No. 443,849

20 Claims. (Cl. 25—118)

The present invention is directed to the treatment of piles, particularly those located under water, for the purpose of repairing the same and preventing erosion.

In my prior Patent No. 2,189,028, issued February 6, 1940, I have described a process wherein a form was placed around the eroded portion of a pile, and concrete poured into the same in a special manner, the concrete being allowed to set to form a reinforcement for the pile. According to said patent, the form which was used was so constructed that it could be removed and used over and over again. Also, by the use of the form, it was sometimes difficult to seal off the bottom, when short jackets are required or where the pile was irregular in shape or had an obstruction. This caused the loss of some concrete during the pouring operation.

The present invention is intended and adapted to improve upon the invention of my prior patent, it being among the objects thereof to provide a form for holding the concrete during the pouring and setting thereof which will prevent leakage or loss of concrete in the operation.

It is also among the objects of the present invention to provide a means for recovering the form after the concrete has set, even though the operation has been conducted under water, without the necessity of any operator going under water in order to disassemble the form.

In practicing the present invention I provide a form usually made of a single sheet of steel or the like, having its two longitudinal edges bent outwardly to form flanges, and means are provided for holding the flanges together in order to close the side of the form. The lower end of the form is closed by a flexible member usually in the form of a tube which is held in the bottom of the form by temporary securing means. The open form is placed around the pile, the side edges are secured together, the tube is placed in its lower end, and the assembly is then lowered through the water to the position on the pile where the concrete is to be cast.

Means are provided for extending the tube in order to close the bottom and to prevent leakage of cement or concrete. The tube may be of several types. One type which has been found quite desirable consists of an open-ended rubber tube which is adapted to be placed around the pile so that its ends overlap. A source of air capable of manipulation from above is attached to the tube, and after the form is in place, the tube is inflated to extend it against the form and the pile, providing a tight seal.

Another form of tube adaptable for the purpose, and not requiring inflation, is filled with a soft slurry of cement, plaster or concrete which is placed in the bottom of the form and held in position. As the concrete is poured on top of the same it distorts the soft filled tube and extends it to provide a tight seal.

After the concrete has been set, the inflatable tube may be removed. This is accomplished by first removing the means which held the tube in the form, then deflating the same and spreading the ends of the tube apart. All these operations may be conducted by means of suitable wires or cords manipulated from above the water line. Then, the entire tube may be pulled from above and removed from the form.

The invention also contemplates means for opening the form itself and removing the same from around the concrete reinforcement. This is accomplished by providing the meeting flanges with temporary locking means which are adapted to be removed by manipulation from above the water line. Several types of locking arrangements may be used, as for example, a series of fork members or adjustable clamps straddle the edges of the flanges all along its length. These members are interconnected by a chain, cable, or the like, having slackness between the adjacent forks. Pulling the chain from above exerts force which loosens the uppermost of the forks and thereafter successively loosens each of the other forks. By this means, but very little tension is required for unlocking the form, no matter how long the form may be, nor how difficult it would ordinarily be to unlock the same.

After the side flanges have been released, the form tends to spring open at least partially by reason of the springiness inherent in the metal. Connections are provided whereby the thus opened form may be pulled up out of the water.

By means of the present invention it is possible to assemble the form completely above the water line, then lower it into the desired position for the pouring of the concrete. The inflation of the tube automatically centers the form so that an equal thickness of concrete is obtained all around the pile. It is unnecessary to do any of the work under water, so that a platform may be provided either on the pier or even below the floor of the pier, and all of the operations conducted regardless of the tide or weather.

After the concrete has set, the removal of the form is a very simple operation, requiring only the pulling of a few cords, cable, or chains, and

the form is then in condition for immediate use by closing it around an adjacent pile.

In the accompanying drawings constituting a part hereof and in which like reference characters indicate like parts:

Fig. 1 is an elevational view of my new apparatus being lowered into operative position;

Fig. 2 is a similar view showing the device in its final position just prior to being disassembled and removed;

Fig. 3 is a view from below of Fig. 2;

Fig. 4 is an elevational view of the inflatable tube;

Fig. 5 is an enlarged detail view of the locking fork;

Fig. 6 is a fragmentary elevational view of a modified form of locking arrangement;

Fig. 7 is an end view thereof;

Fig. 8 is an elevational view of a form having a special arrangement in the bottom thereof for holding the tube;

Fig. 9 is a bottom view thereof;

Fig. 10 is a fragmentary elevational view of a modification of Fig. 8;

Fig. 11 is a bottom view of Fig. 10;

Fig. 12 is a horizontal cross-sectional view of a modified form of the device;

Fig. 13 is a vertical cross-sectional view taken along the line 13-13 of Fig. 12;

Fig. 14 is a similar view taken along the line 14-14 of Fig. 12 of a modified form;

Fig. 15 is a plan view of a modified form of locking arrangement;

Fig. 16 is side elevational view thereof;

Fig. 17 is an elevational view showing an assembly of devices adapted to accomplish the desired result; and

Fig. 18 is a horizontal cross-sectional view taken along the line 18-18 of Fig. 17.

Referring to Fig. 1, the pile 1 is in position, being held below the mud line, the low water line being indicated at 2 and the high water line at 3. A form 4 made of bent sheet metal has along the lateral edges thereof, members 5 secured thereto and terminating in longitudinal flanges 6, as shown in Fig. 3. Ears 7 are secured to form 4 at opposite sides near the top thereof, and chains 8 are secured thereto for hoisting purposes.

The flanges 6 are secured together by means of a series of clips or clamps 9 having forked ends 9' and round bars 10 welded to the tops thereof. The opposite ends are provided with openings wherein a chain 11 is adapted to be secured. As shown in Figs. 1 and 2, the portions 12 of the chain between the adjacent clips are loose. Recesses 13 are provided in flanges 6, serving as seats for members 10 and providing a fulcrum.

In order to close the bottom of the form, there is provided an inflatable rubber tube 14, the ends 15 and 16 thereof being sealed and being beveled as shown at 17 in order that the two ends may fit together to form a circle, as shown in Fig. 4. An opening 18 provides means for inflating the tube. It is placed in position and enclosed in a cover 19 whereby it covers the entire open end of the form and holds concrete in place. An opening 20 in cover 19 provides means for an inflating tube connection to 14. The free end 21 of cover 19 fits into the opposite end 22 which has a slit therein provided with grommets whereby the entire assembly may be closed by lacing. Tabs 24 are located at both ends of cover 19 and cords, or the like, are adapted to

be attached thereto whereby, upon pulling on the cords, the ends of 19 and 14 may be opened for removal.

A block 25 of wood, or the like, is placed within portions 5 to fully close the form. The connection at 18 terminates in a tube 21 reaching to above the water line.

A series of loops 27 which may be rubber bands, cords, wires, or the like, surround casing 19 and extend through a series of openings 28 in form 4. A wire, or the like 29 is threaded through the loops on the outside of the form and an eye 30 is attached to a central portion of 29. A cord, or the like 31 secured to eye 30 reaches above the water line for manipulation.

In the modification shown in Figs. 6 and 7, the flanges 6 have diagonal slots 32 with capscrews having washers 34 welded to the head of capscrews 33, inserted into the bottom of the slots 32. Levers or bars 35, which revolve about $\frac{1}{4}$ turn on capscrews 33, and having openings 36, are fitted over heads 33. At the opposite end of levers 35 are openings 38 to which the chain 11 is secured.

In Figs. 8 and 9 is shown a means for holding the tube 19 in place. It consists of a door 39 hinged at 40 to form 4 and a similar door 41 hinged to the opposite side at 42. An overlap 43 on door 41 holds door 39 in place. Cables 44 are attached to extension 43 and the upper ends thereof 45 are provided with hooks which are attached to the upper edge of the form 4.

In Figs. 10 and 11 is shown a modification of means for holding the tube 19. There is provided a pair of flat bars 46 and 47 secured to bar 48 at the bottom of form 4. A similar bar 49 is held by bars 46 and 47 without being secured thereto. At the corners 50 of the rectangle are secured cables 51 extending upwardly and being secured by turn buckle hooks 52 to the top of the form.

In Figs. 12 to 14 is shown a further modification of the invention. The pile 53 is rectangular in outline with flattened corners, so that the cross-section is an octagon. The form 4' made in two halves, is closed around the pile. A tube 54 has a beveled, flattened portion 55 at both ends. A similar tube 56 has a flattened portion 57 at both ends similar to the tube shown in Fig. 4. However, the tubes 54 and 56 are filled with a semi-liquid cement or concrete and water mixture 59, so that they are capable of being deformed. When introduced into the form, they are in the shape of a circle 60 which, by the weight of concrete poured on top thereof, is flattened as shown in Figs. 13 and 14. When piles are badly deteriorated there is provided a block 61 in order to give the proper contour to the tube 54. Said tube is supported and held in place by angle members 58 secured to and made part of the form.

In place of the clamps or clips above described, one may use a form such as is shown in Figs. 15 and 16. It consists essentially of a pair of jaws 62 and 63 held together by a screw 64 passing through jaw 62 and threaded into jaw 63. A screw 65 in the end of jaw 63 and threaded into the same, contacts with a depressed portion 66 in jaw 62. A section of a round rod 67 which acts as a fulcrum is welded to jaw 62.

In Figs. 17 and 18 there is shown a modification of the invention whereby a standard form may be used for casting a relatively long repair section. There is provided a form 68 similar to that described above, and a form 69 contacting with

the bottom thereof. The additional form is made up of two substantially semi-circular sections 69 and 70 having flanges 71 and 72. These flanges are secured together by suitable clips or clamps, as described above. Chains 73 are provided for hoisting said section. A pipe 74 terminating in nozzles 75 is secured to member 69. A pair of plates 76 secured to members 69 and 70 provide means for holding form 68 in the proper relative position. A pair of additional forms 78 are superimposed upon the lower form and are held in place by plates 77 similar to plates 76. Suitable chains 79 are provided whereby each section of the form may be loosened from the next lower section and thus enable the entire assembly to be removed without exerting any undue force.

There are many advantages inherent in the new construction. It enables quick repairs to be made under various conditions and in most cases the structure is usable during the operations. Various changes in the construction of the apparatus will suggest themselves within the spirit of the invention, the scope of which is defined in the claims appended hereto.

What I claim is:

1. Apparatus for casting concrete around piles comprising a form having a side opening adapted to surround a pile, means for closing the side of said form, a flexible tube in the bottom of said form, said tube closely fitted between said pile and form to cover the open end of said form, said tube being supported through the side of said form, means for inflating said tube to close said bottom and to center said form relative to said pile, and means for deflating said tube and for removing the same from said pile while said form is in place.

2. Apparatus for casting concrete around piles comprising a form having a side opening adapted to surround a pile, means for closing the side of said form, a flexible tube in the bottom of said form, said tube closely fitted between said pile and form to cover the open end of said form, said tube being supported through the side of said form, a fluid setting mixture contained therein, means for inflating said tube to close said bottom and to center said form relative to said pile, and means for deflating said tube and for removing the same from said pile while said form is in place.

3. Apparatus for casting concrete around piles comprising a form having a side opening adapted to surround a pile, means for closing the side of said form, a flexible tube in the bottom of said form, said tube closely fitted between said pile and form to cover the open end of said form, said tube being supported through the side of said form, means for inflating said tube with gas to close said bottom and to center said form relative to said pile, and means for deflating said tube and for removing the same from said pile while said form is in place.

4. Apparatus for casting concrete around piles comprising a form having a side opening adapted to surround a pile, means for closing the side of said form, a flexible tube in the bottom of said form, said tube closely fitted between said pile and form to cover the open end of said form, said tube being supported through the side of said form, a jacket surrounding said tube, means for inflating said tube to close said bottom and to center said form relative to said pile, and means for deflating said tube and for removing the same from said pile while said form is in place.

5. Apparatus for casting concrete around piles

comprising a form having a side opening adapted to surround a pile, means for closing the side of said form, a flexible tube held in the bottom of said form, a plurality of openings in the lower portion of said form, holding members on said tube extending through said openings, means threaded through said members on the outside of said form to hold said tube in place, and means for inflating said tube to close said bottom and to center said form relative to said pile.

6. Apparatus for casting concrete around piles comprising a form having a side opening adapted to surround a pile, means for closing the side of said form, a flexible tube held in the bottom of said form, a plurality of openings in the lower portion of said form, holding members on said tube extending through said openings, means threaded through said members on the outside of said form to hold said tube in place, and means for inflating said tube to close said bottom and to center said form relative to said pile, and a pull cord attached to said threaded means for removing the same from said members.

7. Apparatus for casting concrete around piles comprising a form having a side opening adapted to surround a pile, means for closing the side of said form, a flexible tube in the bottom of said form, and means for inflating said tube to close said bottom and to center said form relative to said pile, said tube being of annular shape with free ends which overlap so that said tube is closely fitted between said pile and form, said tube being free from supports below the same, whereby it may be removed from below.

8. Apparatus for casting concrete around piles comprising a form having a side opening adapted to surround a pile, means for closing the side of said form, a flexible tube held in the bottom of said form, and means for inflating said tube to close said bottom and to center said form relative to said pile, said tube being of annular shape with free ends and having pull tabs adjacent said ends, whereby said tube may be pulled open.

9. Apparatus for casting concrete around piles comprising a form having a side opening adapted to surround a pile, means for closing the side of said form, a flexible tube held in the bottom of said form, a jacket surrounding said tube, and means for inflating said tube to close said bottom and to center said form relative to said pile, said tube and jacket being of annular shape with free ends, pull tabs on said jacket adjacent said ends, whereby said tube and jacket may be pulled open.

10. Apparatus for casting concrete around piles comprising a form having a side opening adapted to surround a pile, means for closing the side of said form, a flexible tube held in the bottom of said form, a jacket surrounding said tube, and means for inflating said tube to close said bottom and to center said form relative to said pile, said tube and jacket being of annular shape with free ends, one end of said jacket being slit to allow the opposite end of said jacket and tube to be inserted therein, and means for lacing up said slit portion.

11. Apparatus for casting concrete around piles comprising a form having a side opening adapted to surround a pile, means for closing the side of said form, a flexible tube held in the bottom of said form by a closed hinged door arrangement secured to said bottom and adapted to be opened.

12. Apparatus for casting concrete around piles comprising a form having a side opening adapted to surround a pile, meeting flanges along said side, and means for clamping said flanges to-

gether including a plurality of longitudinally spaced clamps, said clamps being interconnected by slack connectors between adjacent clamps, and a single means for releasing all of said clamps, said clamps being detachable from said form.

13. Apparatus for casting concrete around piles comprising a form having a side opening adapted to surround a pile, meeting flanges along said side, and means for clamping said flanges together including a plurality of longitudinally spaced clamps, said clamps being interconnected by slack connectors between adjacent clamps, and a single means for releasing all of said clamps successively to allow complete separation of said flanges and opening up of said form.

14. Apparatus for casting concrete around piles comprising a form having a side opening adapted to surround a pile, meeting flanges along said side, and means for clamping said flanges together including a plurality of longitudinally spaced clamps, said clamps being interconnected by slack connectors between adjacent clamps, each clamp having a fork adapted to embrace said flanges, a fulcrum bar attached thereto, a recess in said flanges for said bar, and a single means for releasing all of said clamps.

15. Apparatus for casting concrete around piles comprising a form having a side opening adapted to surround a pile, meeting flanges along said side, and means for clamping said flanges together including a plurality of longitudinally spaced clamps, said clamps being interconnected by slack connectors between adjacent clamps, each clamp having a fork adapted to embrace said flanges, a fulcrum bar attached thereto, a recess in said flanges for said bar, and a single means for releasing all of said clamps including a pull device adapted to rotate said fork to a position out of contact with said flanges.

16. Apparatus for casting concrete around piles comprising a form having a side opening adapted to surround a pile, meeting flanges along said side, and means for clamping said flanges together including a plurality of longitudinally spaced clamps, said clamps being interconnected by slack connectors between adjacent clamps, each clamp having a fork adapted to embrace said flanges, a fulcrum bar attached thereto, a recess in said flanges for said bar, mechanism for adjusting the width of the space within said fork, and a single means for releasing all of said clamps.

17. Apparatus for casting concrete around piles comprising a form having a side opening adapted to surround a pile, meeting flanges along said side, and means for clamping said flanges together including a plurality of longitudinally spaced clamps, said clamps being interconnected, each clamp having a bolt adapted to hold said flanges together, a slot in said flanges extending downwardly and inwardly from the edges thereof, said bolt being held therein, and a single means for releasing all of said clamps.

18. Apparatus for casting concrete around piles comprising a form having a side opening adapted to surround a pile, meeting flanges along said side, and means for clamping said flanges together including a plurality of longitudinally spaced clamps, said clamps being interconnected, each clamp having a bolt adapted to hold said flanges together, a slot in said flanges extending downwardly and inwardly from the edges thereof, said bolt being held therein, a bar attached to the bolt adapted to turn the same when manipulated, and a single means for releasing all of said clamps.

19. Apparatus for casting concrete around piles comprising a form having a side opening adapted to surround a pile, meeting flanges along said side, and means for clamping said flanges together including a plurality of longitudinally spaced clamps, said clamps being interconnected, each clamp having a bolt adapted to hold said flanges together, a slot in said flanges extending downwardly and inwardly from the edges thereof, said bolt being held therein, a bar attached to the bolt adapted to turn the same when manipulated, and a single means for releasing all of said clamps secured to each of said bars.

20. Apparatus for casting concrete around piles comprising a form having a side opening adapted to surround a pile, means for closing the side of said form, a pair of flexible tubes in the bottom of said form, each of said tubes surrounding about one-half of the circumference of said pile, the ends of said tubes being overlapped, and means for inflating said tubes to close said bottom and to center said form relative to said pile, said tubes together having an approximately annular shape with free ends which overlap so that said tube is closely fitted between said pile and form, said tube being supported through the side of said form whereby it may be removed from below.

THORWALD H. HANSEN.
